UNITED STATES PATENT OFFICE

125,016

DESIGN FOR A DRESS

Eleanor Hill Bushnell, New York, N. Y.

Application September 26, 1940, Serial No. 95,397

Term of patent 3½ years

To all whom it may concern:

Be it known that I, Eleanor Hill Bushnell, a citizen of the United States, residing at 42 Riverside Drive, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown and described.

ELEANOR HILL BUSHNELL.
